US00D870366S

(12) **United States Design Patent** (10) Patent No.: **US D870,366 S**
(45) Date of Patent: **** Dec. 17, 2019**

(54) **HANDHELD AEROSOL GENERATOR**

(71) Applicant: **PHILIP MORRIS PRODUCTS S.A.**,
Neuchâtel (CH)

(72) Inventors: **Frédéric Lavanchy**, Chavornay (CH);
David Kuchen, Vallamand-Dessous
(CH); **Stéphane Roudier**, Colombier
(CH); **Anthony Dumville**, Epesses
(CH)

(73) Assignee: **PHILIP MORRIS PRODUCTS S.A.**,
Neuchâtel (CH)

(**) Term: **15 Years**

(21) Appl. No.: **35/503,721**

(22) Filed: **Mar. 27, 2017**

(80) **Hague Agreement Data**

Int. Filing Date: **Mar. 27, 2017**

Int. Reg. No.: **DM/096906**

Int. Reg. Date: **Mar. 27, 2017**

Int. Reg. Pub. Date: **Sep. 29, 2017**
